Primary Examiner — Susan Bennet Hattan*Assistant Examiner* — Marie D. Fast Horse(74) *Attorney, Agent, or Firm* — Ralph E. Smith(57) **CLAIM**

The ornamental design for an automobile wheel, as shown and described.

DESCRIPTION

FIG. 1 is a left side perspective view of an automobile wheel showing our new design;

FIG. 2 is a front view thereof; and,

FIG. 3 is a right side perspective view.

The broken lines shown in the drawings depict portions of the automobile wheel that form no part of claimed design.
